2.5 is an exploded perspective view of the top lid interior.

2.6 is an exploded perspective view of the interior body portion.

2.7 is an exploded perspective view.

3.1 is a perspective view of another embodiment shown closed.

3.2 is a perspective view of the top lid interior.

3.3 is an exploded perspective view of the top lid interior.

3.4 is an exploded top plan view.

3.5 is an exploded front elevation view.

3.6 is an exploded perspective view of the interior body portion.

3.7 is an exploded perspective view.

4.1 is a perspective view of another embodiment shown closed.

4.2 is an exploded top plan view.

4.3 is perspective view of the top lid interior.

4.4 is an exploded perspective view of the top lid interior.

4.5 is an exploded perspective view.

4.6 is an exploded front elevation view.

4.7 is an exploded perspective view of the interior body portion.

5.1 is a perspective view of another embodiment shown closed.

5.2 is an exploded perspective view.

5.3 is perspective view of the top lid interior.

5.4 is an exploded top plan view.

5.5 is an exploded perspective view of the top lid interior.

5.6 is an exploded front elevation view.
